UNITED STATES PATENT OFFICE.

HENRY ROSENBLATT, OF NEW YORK, N. Y., ASSIGNOR TO PLYMOUTH NOVELTY CO., INC., OF NEW YORK, N. Y., A CORPORATION OF NEW YORK.

DESIGN FOR A BUTTON FOR PICTURE OR MIRROR CORD.

Application filed February 2, 1926. Serial No. 16,372. Term of patent 7 years.

To all whom it may concern:

Be it known that HENRY ROSENBLATT, a citizen of the United States, and resident of New York city, in the county of Kings and State of New York, has invented a new, original, and ornamental Design for Button for Picture or Mirror Cord, of which the following is a specification, reference being had to the accompanying drawing, forming part thereof, in which—

Fig. 1 is a front elevational view of a button for picture or mirror cord embodying the design of my invention; and

Fig. 2 is a side elevational view of the new button for picture or mirror cord, the hook whereby the cord is suspended being shown in dotted lines.

I claim:

The ornamental design for a button for picture or mirror cord as shown.

Dated New York city, January 28th, 1926.

HENRY ROSENBLATT.
